ATTORNEY

UNITED STATES PATENT OFFICE.

CHARLES H. COWAN, JR., OF STONINGTON, CONNECTICUT.

HAT-HOLDING DEVICE.

Application filed September 26, 1928. Serial No. 308,437.

The object of this invention is to provide a device of the character indicated which shall include a plurality of jaws adapted to engage the sweat band of a hat, or the inner portion of the crown, and mounting means for the jaws comprising a forked resilient structure having offset portions in the arms thereof, and the ends of the arms entering the inner portions of the jaws, said jaws having their approaching ends slotted and the slotted portions being engaged by the respective arms of the fork.

With the foregoing and other objects in view, the invention consists in the novel construction and arrangement of elements described, illustrated and claimed, it being understood that modifications may be made within the scope of the claims without departing from the spirit of the invention.

20 In the drawing forming part of this application,

Figure 1 is a plan view of the device, with a portion of one jaw member broken away to show its engagement with an element of the fork.

Figure 2 constitutes a section through the crown and brim of the hat, the hat holding device being in elevation.

Figure 3 is a fragmentary view showing the device carried by the arms of the fork as having been shifted from the position of Figure 1 to a position changing the relative position of the jaws.

Figure 4 is a detail view on line 4—4 of Figure 1, and shows the relation of the elements of the fork to the jaws, at their slotted ends, and also shows the connecting device between the elements of the fork, adjacent to the offset portions thereof.

40 The jaws are numbered 10 and 11, and each jaw may be provided with an outer covering of fabric or felt such as 12 if desired. This covering element tends to prevent slipping of the holding device with reference to the sweat band of the hat.

Each jaw includes, or may include, an enlarged portion such as 13, apertured at 14 for the ends of a fork or U-shaped metallic element comprising the outer portions 15, the diverging portions 16, the offset portions 17, and the handle portions 18. The latter merge into the U-shaped end 19.

Each jaw is provided with an inner slotted end, the slots being shown at 20, and being adapted to receive the portions 16 of the

forked member. Owing to the shape of the fork, and the positive mounting at 14 of the end portions thereof, the inner ends of the jaws will maintain operative relation with the forks, but pins may also be provided if desired at the point or points 21.

The portions 18 of the fork are adjustably connected by a link or a plurality of connected links, as shown at 22, the ends of the links including ring members slidable with reference to the portions 18 of the fork.

In Figure 1 the diverging portions of the fork, and the jaws, are shown as expanded, or in position for positively engaging the sweat band of the hat, in order that it may be held in the hands, or suspended from a hook or the like 24. Under these circumstances the links are positioned adjacent to the offset portions 17, but under the conditions of Figure 3, the links have been moved longitudinally of the handle formed by the portions 18 and the jaws have approached each other, as they would do under pressure by the hand of the user, the links 22 then being shifted if desired to maintain that position, for the time being.

The device is suitable for use under ordinary circumstances, wherein it is desired to suspend or support a hat from a hook or the like without danger of its being readily displaced by air currents and the like and the device is also suitable for use by those desiring to properly support a hat while the latter is being cleaned, the handle portions then being held by the operator.

Having described the invention what is claimed is:

1. In a device of the character described, a plurality of jaws of segmental form and having their approaching ends spaced and slotted, and a resilient forked element engaging the slotted portions and having connection with the jaws intermediate of the ends thereof.

2. In a device of the class described, a plurality of jaws of segmental form and having corresponding ends approaching each other, a resilient forked member including arms engaging the approaching ends and being connected with the jaws intermediate of the ends thereof said forked member including a handle portion, and means controlling the extent of spread of the arms of the fork.

3. In a device of the class described, a plurality of jaws of segmental form and having corresponding ends approaching each other,

a resilient forked member including arms engaging the approaching ends and being connected with the jaws intermediate of the ends thereof, said forked member including a handle portion, and means controlling the extent of spread of the arms of the fork, the arms being offset and the means controlling

the extent of spread being adapted to engage the offset portion, and being slidable therefrom to the main portions of the arms, for reducing the space between the jaws and freeing the latter from the hat. ¹⁰

In testimony whereof I affix my signature.
CHARLES H. COWAN, Jr.
